PRINTING PRESS ROLL STRUCTURE

George Goebel, deceased, late of Baltimore, Md., by Helene Goebel, administratrix, Baltimore, Md., and Eibe A. Wilckens, Baltimore, Md., assignors to Crown Cork & Seal Company, Inc., Baltimore, Md., a corporation of New York

Original application October 1, 1936, Serial No. 103,592. Divided and this application May 3, 1940, Serial No. 333,252

12 Claims. (Cl. 101—351)

The present invention relates to printing press roll structures, being a division of the application for printing presses of George Goebel and Eibe A. Wilckens, Serial No. 103,592, filed October 1, 1936, issued June 25, 1940, Patent No. 2,205,720.

An important object of the invention is to provide a press which will be capable of high speed production of uniformly printed sheets, all of the mechanisms of the press being so designed that sheets to be printed or lithographed will be properly fed between the cylinders and the cylinders maintained in proper position for efficient printing action.

Still another object of the invention is the provision of fluid pressure operated means to control the position of the ink form rolls, and valves for controlling these means with a wide range of selectivity.

Another object of the invention is to provide a mounting for the ink form rolls whereby these rolls may be readily adjusted to contact both with the larger inking rolls and the plate cylinder.

In order to enable the ink form rolls to be properly positioned with respect to both the ink roll and the plate cylinder, their journals must be movable both radially and circumferentially with regard to the plate cylinder. By the present invention, adjustments in both directions may be readily obtained through a very simple mechanism.

Another object of the invention is to provide a mounting for the smaller rolls of a press which will permit such rolls to be bodily removed or replaced with considerably more facility than has heretofore been possible.

Still another object of the invention is to provide an improved mounting for the inking cylinder of a press.

In order that the ink on the inking cylinder may be properly distributed upon the various ink rolls, it is necessary to have the inking cylinder reciprocate axially while it is rotating. This movement has ordinarily been accomplished by having the shaft of the inking cylinder reciprocate as well as rotate in its bearings. The mechanism necessary to accomplish this movement is relatively complicated and readily subject to wear and the reciprocation of the shaft as well as the cylinder necessarily requires greater power than would be the case if the cylinder, alone, were reciprocated upon the shaft. By the present invention, the cylinder is reciprocated upon its shaft, the shaft having only a rotary movement.

Other objects and advantages of the invention

will be apparent from the following specification and drawings, wherein,

40 *Summary of construction and operation*

The construction and operation of the press may be generally described as follows:

Referring to Figure 1, the numeral 38 indicates the upper or plate cylinder of the press which receives ink from the ink form rollers generally designated by the numeral 40. Beneath the plate cylinder there is provided the intermediate or transfer cylinder 41 which is provided

50 with a transfer blanket to receive the impression from the plate cylinder 38 and print it upon a sheet as the latter passes through the printing couple formed by the transfer cylinder 41 and the lower or impression cylinder 42. The sheet to be printed upon is fed from the feed table 43

by suitable mechanism so that in the normal operation of the press, as described in Patent No. 2,205,720, issued June 25, 1940, said original application, Serial No. 103,592, at a predetermined moment in each rotary movement of the cylinders, a sheet to be printed or lithographed should be positioned on the feed table 43. If the sheet is so positioned, it will force a trip finger 46 downwardly and the sheet trip mechanism 47, best shown in Figure 8, will thereby operate in the normal manner to maintain an automatic valve mechanism 48 controlling fluid flow circuits in such position that the fluid-pressure in such circuits will support or hold the impression cylinder 42 upwardly in contact with the transfer cylinder 41. However, assuming that a pair of manual valves 49 and 50 also included in the fluid flow circuits are in their normal position for the running of the press, should no sheet be on the feed table at the proper moment, the trip finger 46 will remain in the upward position shown in Figure 1, with the result that the operation of the trip mechanism 47 will be varied and the automatic valve mechanism 48 will be actuated to so change the fluid pressure flow that impression cylinder 42 will drop out of contact with the transfer cylinder 41, thereby preventing the transfer cylinder from printing upon the impression cylinder, as it would do if the two cylinders were left in normal position with no sheet passing between them.

Actuation of manual valve 49, the "impression" valve, to "off" position, will permit the ink form rolls 40 to be manually moved either into or out of contact with the plate cylinder 38, and will cause the impression cylinder 42 and the transfer cylinder 41 to drop with respect to the plate cylinder 38, the impression cylinder dropping a greater distance than the transfer cylinder, thereby avoiding contact with the transfer cylinder, all regardless of whether sheets are passed through the printing couple. Actuation of manual valve 50, the "ink" valve, to "on" position will permit the ink form roll throw-out mechanism to be manually operated regardless of whether sheets are passed through the printing couple.

Press cylinder drive

In the following description of the press, the front is regarded as the feed table end and the rear is regarded as the side from which printed sheets emerge.

The press includes a base 60 having side plates extending upwardly therefrom, the left hand side plate being designated 61 and the right hand side plate being designated by the numeral 62. Power is provided from a motor 63 which acts through a belt or the like 64 to drive a large pulley 65 fixed to a shaft 66 journaled in the right hand side plate 62. The shafts 70 and 71 of the transfer cylinder 41 and the plate cylinder 38, respectively, are driven from shaft 66 as described in said original application. The plate cylinder 38 is journaled in the upper portion of the side plates of the press and has no vertical movement but the shafts 69 and 70 of the impression and transfer cylinders, respectively, are journaled in boxes 72 and 73, respectively, vertically movable in the side plates of the press through a mechanism hereinafter described.

The ink cylinder 80 and the form rollers associated therewith are driven (Figure 2) from a drive gear 81 provided on the shaft 71 of the plate cylinder 38, the gear 81 meshing with a small pinion 82 journaled on a stud 83, pinion 82

driving a pinion 84 fixed to the shaft 85 carrying the ink cylinder 80. The above mechanism is provided within the left hand side plate 61 of the press and, as shown in Figure 4, the right hand end of ink cylinder shaft 85 is provided with a worm gear 86 which drives a worm wheel 87 fixed to a shaft 88 journaled in a housing 89 secured to the right hand side plate 62. Shaft 88 is provided with an eccentric 90 which operates a connecting rod 91 having its inner end pivotally connected to a yoke 92 pivoted intermediate its ends at 93 to a bracket 94 fixed to the side frame 62. The lower arms 95 of the yoke carry blocks engaged in a circumferential groove 96 in a sleeve 97 fixed to the ink cylinder 80. By this arrangement, the inking cylinder 80 will be reciprocated or vibrated on its shaft 85 as it is rotated with the shaft. The upper arms of the yoke 92 carry blocks positioned between spaced flanges on a distributor roller 98 so that the latter may be vibrated and a second circumferential groove 99 is provided on the sleeve 97 to operate other rocking levers, such as 100, to vibrate other form or rider rollers in the usual manner.

The construction of the ink cylinder 80 to permit it to be reciprocated on its shaft 85 as it rotates is as follows: The sleeve 97 supports one end of the inking cylinder, the other end being supported by a sleeve 101 of generally similar construction except that it is not provided with any rocker arm operating grooves. Each of the sleeves 97 and 101 closely embraces the shaft 85 and each sleeve is counter-bored as indicated at 102 to receive the outer race 103 of a roller bearing 104, the inner races 105 being carried on the shaft 85. It will be observed that the sleeves 97 and 101 are further chambered as indicated at 106 for a purpose hereinafter set forth. The sleeves 97 and 101 are each provided with an annular flange 107 bolted to inwardly extended flanges on the cylinder 80, the inner ends of the sleeves having bolted thereto annular collars 108 provided with flanges 109 bearing against the inner edges of the outer races 103 of the roller bearings 104. A ring 110 is positioned within each collar 108, the inner edges of the rings bearing against shoulders 111 formed by a central enlargement of shaft 85 and the opposite edges of the rings bearing against the inner races 105. Yokes 112 extend inwardly from the inner faces of the collars 108, the inside surfaces of the yokes embracing rollers 113 rotatable on pins 114 secured in the shaft 85, as shown in Figure 5.

By the above arrangement, when the sleeve 97 is moved lengthwise of shaft 85 by the action of the eccentrically operated connecting rod 91, the ink cylinder 80 and its supporting sleeves 97 and 101 will be given a corresponding movement, the cylinder moving with respect to the shaft 85 while rotating upon the roller bearings 104, the outer races 103 of the bearings moving relative to the inner races 105 upon the balls of the bearing. The desired axial or rectilinear movement of the cylinder with respect to the shaft will be assured by the provision of the yokes 112 embracing the rollers 113. The provision of the chambers 106 in the sleeves 97 and 101 enables the sleeves to move over the inner race-ways 105 during the reciprocation or vibration of the cylinder 80.

It will be understood that the "vibration" of the cylinder 80 as well as the vibration of various form rollers is a result of the reciprocation of the cylinder and various rolls while being rotated.

The above arrangement whereby the cylinder 80 is vibrated upon its shaft 85, instead of the usual arrangement of having the shaft vibrated with the cylinder eliminates the necessity of a substantial portion of the driving power which has heretofore been necessary to vibrate the relatively heavy cylinder shaft with the cylinder and eliminates the sliding friction in the driving gears.

The dampening mechanism 115 (Figure 1) of the present press is of the usual construction and includes the ductor roll 51 which transfers water from the fountain roll 116 to a form roller 117 which in turn places the water upon a pair of dampening or water rolls 118. The mechanism for oscillating the water ductor roll 51 is described in our application for printing press dampening roll control filed of even date herewith, which issued as Patent No. 2,310,363, on February 9, 1943, and which is also a division of said original Goebel and Wilckens application.

Roll supporting mechanism

Figure 9 best illustrates the manner in which various rolls to supply ink or water to the press couple are mounted so that they may be readily removed. Figure 9 shows the mounting as applied to one of the ink form rolls 40. It will be observed from this figure that the ends 184 of the roll are carried in anti-friction bearings 185, the bearing at one end of the roll, the end at the right hand side of the press, is carried in a bracket 192a of generally cup-shaped form, the other bearing 185 being carried in a holder 186 mounted in a split bracket 192, both brackets 192 and 192a being mounted in socket members 193 hereinafter described and which are secured to hangers 194 pivotally hung from the upper portion of the press in a manner hereinafter set forth. The split bracket 192 is normally clamped about the holder 186 by means of a bolt 187. When it is desired to remove a roll such as 40, it is only necessary to loosen the bolt 187 so that the holder 186 may be withdrawn or moved to the left in Figure 9, releasing the left hand end of roll 40 so that the right hand end may be withdrawn from the bearing 185 in bracket 192a.

The form roller throw-out mechanism

The ink form rolls 40 provided for the purpose of transferring ink from the large form roll 190 to the plate cylinder 38 are arranged for circumferential and radial adjustment with respect to the plate cylinder by the construction of the brackets 192 and 192a referred to above and the manner in which the latter are supported on the hangers 194 swung from a collar 195 (Figures 2 and 4) secured to each side frame of the press in alignment with the ink cylinder shaft 85.

The inner portion of each bracket 192 is squared as indicated at 199 to fit between shoulders 200 on a socket member 193, thereby obviating possibility of the bracket turning with respect to the socket member. A stud 201 projects into each socket from the corresponding bracket and the extreme inner end of the stud is reduced and threaded as indicated at 201a and carries a nut 202 which is positioned within a cut-out 203 in the socket 193. It will thus be obvious that rotation of the nut 202 will move the bracket 192 radially of the plate cylinder 38.

In order to permit each form roller 40 to be adjusted circumferentially of the plate cylinder 38, each socket member 193 is provided on its rear face with a shoulder 205 of arcuate form which engages an arcuate groove 206 in the outer

face of the corresponding hanger 194. Studs 208 are secured in apertures spaced in the arcuate grooves 206 and each stud carries a sleeve 209 provided with a shoulder 210 (Figure 1) which bears upon the outer face of the corresponding socket member 193, thereby retaining the socket member in the groove 206 and in engagement with the corresponding hanger 194. The periphery 211 of the body portion of the sleeve 209 is eccentric with respect to the bore of the sleeve which fits the corresponding stud and rotation of the sleeve by a tool engaged in pockets of its shoulder 210 will therefore cause the socket to be moved along the groove 206, resulting in adjustment of that ink form roll 40 circumferentially of the plate cylinder. Nuts 212 hold the eccentrics locked.

As indicated in Figure 9, the right-hand and cup-shaped brackets 192a are supported in the socket members 193 and upon the hangers 194 in the same manner as the left-hand brackets 192.

It is necessary in the operation of the press to have the ink form rollers in proper contact with both the periphery of the plate cylinder and the periphery of the large form rolls such as 190 and this can best be obtained through provision for both radial and circumferential adjustment of the form rolls with respect to the plate cylinder.

As indicated in Figure 1, dampening form rolls 118 are mounted similarly to the ink form rolls but in arcuate grooves in the outer faces of brackets 213 pivoted at 213a to each side frame of the press, the brackets 213 being swung outwardly to move the dampening rolls from the plate cylinder by an eccentric 214 provided with an operating handle 214a.

When it is desired to perform any operation upon the plate cylinder preliminary to running of the press, it is desirable to have the ink form rolls 40 moved out of engagement with the plate cylinder. To obtain this action, the hangers 194 at each side of the press, being hung upon the sleeves 195 (Figures 2 and 4) may be swung apart at their lower ends. The hand operating means for this purpose is best shown in Figures 6 and 7 and comprises a hand lever 215, one on each side of the press, each lever being mounted on a stud 216 fixed in a plate 217 overlying the corresponding end of the shaft 71 of the plate cylinder 38. Each lever 215 has a collar 218 formed integrally therewith which fits upon the pin 216, the collar 218 having its peripheral surface provided with two rises 220 which are adapted to act upon rollers 221 rotatably mounted on studs 222 fixed to the lower inner corners of the hangers 194. It will be apparent from this that swinging movement of the levers 215 will cause the rises 220 to force the rollers 221 apart, thereby swinging the hangers outwardly so that the ink form roll 40 will be out of contact with the plate cylinder 38. The ends of the studs 222 are partially cut away to provide inclined faces 223, as shown in Figures 5, 6 and 7, and the outer portion of the sleeve 218 is slotted to carry keepers 224 adapted to respectively engage the inclined faces 223 of the studs 222 to lock the hangers in inward position. The keepers 224 are adjustable with respect to the collar 218 to permit the keepers to draw the hangers tightly together, each keeper being provided with a guide slot 225 through which a machine screw extends and being movable by means of an adjusting bolt 227 in an offset extension at its inner end which bolt

is adapted to bear upon a shoulder on the collar. A lock screw engages each bolt 227 to hold it in adjusted position.

The levers 215 at each side of the press are connected by a shaft 230 rotatable in the frames of the press, each end of the shaft having a lever 231 fixed thereto, the outer ends of these levers being joined to the throw-out levers 215 by links 232 so that operation of one lever will cause the other lever to be similarly actuated. As will be hereinafter described, the throwout levers 215 are also arranged to be operated by fluid pressure to swing the hangers either inwardly or outwardly.

Separating movement of the hangers 194 will actuate a bell crank mechanism 194a (Figures 1 and 7) to throw out the driving pawl connection to the ink fountain 80a in well-known manner.

Referring to Figures 1 and 8, the shafts 70 and 69 of the transfer cylinder 41 and impression cylinder 42, respectively, are supported in boxes 73 and 72, respectively, which are vertically movable in guide openings 310 (Figure 8) in each side frame of the press.

As described in said Patent No. 2,205,720, issued on said original application, Serial No. 103,592, the boxes 72 at each end of the shaft 69 of the impression cylinder are supported upon pistons 325 mounted in cylinders 319 carried in the side frames of the press. Also, the boxes 73 at each end of the shaft 70 of the transfer cylinder 41 are supported upon pistons 335 mounted in cylinders 336 supported in the side frames.

The position of the pistons 325 and 335 and hence of the impression and transfer cylinders is controlled by fluid pressure controlled by the valve mechanism 48, the actuation of the valve mechanism 48 in turn being controlled by trip finger 46 with which sheets contact, a trip lever 347 and a trip lever cam 351 carried on a cam shaft 42, all as described in detail in Patent No. 2,205,720, issued on said original application Serial No. 103,592.

The automatic valve mechanism 48 for controlling the position of the press cylinders with respect to each other is best shown in Figures 10 to 12.

The valve mechanism 48 includes the housing 363 carried on a standard 401 fixed to the press frame adjacent the left side frame 61. As shown in Figure 10, the housing 363 is provided with four valve chambers 402, 403, 404 and 405 closed at their forward or outer ends by caps 406 and each cylinder having a bore 407 extending inwardly therefrom in which a valve stem of a tappet valve for that chamber may move, the stem of the valve preferably being guided in the bore by a sleeve 408. The valves of the cylinders 402 to 405 are respectively designated by the numerals 410, 411, 412 and 413 and each valve is tended to its seat by a spring 414 positioned between the head of the valve and the inner surface of the corresponding valve chamber cap 406. The valves are adapted to be operated by tappets 417 freely mounted on a small shaft 418 fixed to the rear side of the standard 401, one of the tappets 417 being provided for each valve. The tappets are provided at their upper ends with adjusting set screws 419 to contact with the outer ends of the valve stems and the lower ends of the tappets carry rollers 420 arranged to bear upon cam sectors 421 fixed to the rock shaft 364 which carries the rocker arm 362, one cam being pro-

vided for each pair of tappets. Each cam sector includes a low portion 423 and a high portion 424, the high portions of the cams being indented as shown in Figure 11 so that the rollers 420 will be firmly engaged by the high portions of the cams.

As is shown in Figures 11 and 12, the four cam sectors 421 are so arranged with respect to each other that when the tappets of valves 410 and 412 have low portions 423 of their corresponding cam sectors opposite them, permitting these valves to close, high portions 424 of the other two cam sectors will be opposite the tappets of the valves 411 and 413, holding these two valves open. The reverse will be true when rock shaft 364 is rocked to its opposite position through the movement of rocker arm 362 by the sheet trip mechanism in the manner hereinbefore described.

When valve 411 is open, valve chamber 403 will communicate with valve chamber 402 through a port 428. When valve 410 is open, the corresponding valve chamber 402 will be placed in communication with the atmosphere through a port 429. Valve chamber 404 communicates with the adjacent outer valve chamber 405 through a port 430 when valve 412 is open, and when valve 413 is open, valve chamber 405 will be placed in communication with the atmosphere through a port 431.

Compressed air is supplied to the housing 363 from a pump or other suitable source of pressure through a line 432 receiving flow from a supply main 433, line 432 opening to the upper portion of the housing through a port 434 communicating with the two central valve chambers 403 and 404.

As shown in Figure 13, the automatic valve mechanism 48 communicates with the various pressure chambers of the press through manual valve mechanism 49 and 50, a flow line 436 extending from valve chamber 405 to the manual "ink" valve 50, the line 436 opening to the planar valve seat 431 of the valve through a port 438. A flow line 439 extends from valve chamber 402 to the manual "impression" valve 49, line 439 opening to the planar valve seat of disc valve 49 through a port 440.

Valve 49 is manually operated by means of a radially extending handle 443.

"Ink" valve disc 50 is also rotatable by means of a handle 448. The seats for the valves 49 and 50 are bolted in apertures in the side frame 61 as shown in Figure 1 and valve discs of the valves 55 are provided with a series of passages opening to their seat faces as indicated in Figures 13 to 16. The arrangement of these passages as well as the arrangement of the ports in the seats of the two valves will be described in connection with the operation of the valves set forth below.

Flow circuits—normal or "automatic" operation of press

In the normal operation of the press, it is desirable to have the flow passages in such communication with the source of pressure that both the transfer cylinder 41 and the impression cylinder 42 will be in upward position and the ink 70 form rollers 40 will be in contact with the plate cylinder 38, but with the passages further so arranged that if a sheet is not presented on the feed table 43 at the proper moment, the automatic valve mechanism 48 will be actuated to cause the impression cylinder 42 to be dropped

from the transfer cylinder 41 and the ink form rollers 40 moved from the plate cylinder 38. The arrangement of the manual valves 49 and 50 to attain this operation and the corresponding position of the various valves of the automatic valve mechanism 48 which will then be maintained so long as sheets are passing through the press at the proper time is illustrated in Figure 13.

Referring to Figure 13, it will be observed that the manual "impression" valve 49 is at "on" or at left hand position and that the "ink" valve 50 is at "automatic" or left hand position. At this time, so long as sheets are properly positioned on trip finger 46 of the feed table, the cams 421 will be positioned as indicated in Figures 10 to 12, and as diagrammatically indicated in Figure 13, so that automatic valves 410 and 412 will be closed, while the other two automatic valves 411 and 413 will be opened. That is, the high points 424 of the cams 421 operating to valves 411 and 413 will be opposite the tappets of these two valves, while the cams controlling the other two valves will have their low points 423 opposite those valve tappets. With this arrangement, and with sheets properly arriving upon the feed table 43, air will flow to the automatic valve mechanism 48 from the supply main 433 directly through the line 435 to a port 450 in the seat of manual valve 49 and through a passage 451 in the disc 49a back to a port 452 leading to a line 453 communicating with the chamber 336 in which the piston 335 supporting the journal box 73 of transfer cylinder 41 is carried, thereby holding the transfer cylinder in upward position and against the plate cylinder 38.

At the same time, pressure will also flow from the supply main 433 and thence into the automatic valve housing 363 through line 432 and the port 434 which opens to the two central valve chambers 403 and 404. Since valve 411 is open and valve 412 is closed, pressure from the line 432 can only flow past the valve 411 and through the port 428 opening to valve chamber 402. Valve 410 being closed, this pressure will flow from that chamber through a line 439 to port 440 in the seat of manual impression valve 49. With disc valve 49a in the "on" position referred to, this pressure will flow through a passage 457 in valve 49a and through a port 458 in the valve seat to a line 459 which leads to the chamber 319 in which the piston 321 beneath the impression cylinder journal box 72 is carried, thereby holding the impression cylinder 42 in upward position and in contact with the transfer cylinder 41.

Pressure will also flow from the line 459 last referred to and through a branch line 465 to a port 466 in the valve seat of the "ink" valve 50 and through an aligned passage 467 in the ink disk valve 50a, through a port 468 in the valve seat and thence through a line 469 to a chamber 470 formed in a casting 215a (Figures 6 and 7) fixed to the press side frame 61 beneath the form roller hand operating lever 215 and in which chamber there is positioned a piston 471 of a plunger 472 to which the operating handle 215 is connected by a pin 473 carried intermediate the length of the plunger 472. The opposite end of the plunger 472 has a piston face 475 provided thereon which operates in a chamber 476 and also formed in casting 215a and with which a line 477 communicates. The opposite end of line 477 is connected to a port 478 in the valve seat of "impression" valve 49 which at this

time is aligned with one end of a passage 479 in the valve disc 49a, the opposite end of the passage being aligned with a port 480 having a line 481 connected thereto extending to a port 5 482 in the seat of "ink" valve 50, the latter port being aligned as shown in Figure 13 with a passage 483 in the disc of ink valve 50. The opposite end of passage 483 is in communication with the valve seat port 438 with which the line 436 communicates, the opposite end of line 436 opening to the valve chamber 404 of the automatic valve mechanism 48. Since valve 413 of this valve chamber is open, valve chamber 404 is in communication with the atmosphere through the port 431. Thus, no pressure is present in form roller operating pressure chamber 476, and pressure being present in the opposite chamber 470, the ink form rolls 40 will be held locked in contact with the plate cylinder 38 by the locking elements 224 shown in Figure 7.

As shown in Figure 13, a line 459a runs from line 459 to the pressure chamber 319 beneath the right hand end of impression cylinder 42; a line 453a extends from line 453 to the right hand chamber beneath transfer cylinder 41; and lines 469a and 471a extend from ink roll pressure operating chambers 470 and 476, respectively, to the corresponding chambers on the right hand side of the press.

By the above arrangement, the form rollers 40 will be held in contact with the plate cylinder 38 by the pressure exerted in pressure chamber 470, the transfer cylinder 41 will be held upwardly by the pressure in chamber 336, and impression cylinder 42 will be held upwardly by the pressure in chamber 319. Should some object other than a sheet, for example, a wrench, move between the cylinders 41 and 42, the impression cylinder 42 will move downwardly against the action of the spring 328 without varying the pressure flow.

The valves and pressure flow will remain as described above in connection with Figure 13 so long as a sheet is presented at the proper moment upon the trip finger 46 on feed table 43. However, should no sheet be present upon the trip finger 46 at the proper moment, the trip mechanism 47 will be actuated in the manner described in said original application to such position that the tappet cams 421 will swing upwardly from their position as shown in Figure 11 to permit the valves 411 and 413 to close and valves 410 and 412 to open as diagrammatically indicated in Figure 14. Referring to Figure 14, with the valves of the automatic valve mechanism now in the position there illustrated, pressure will be maintained in pressure chamber 336 beneath piston 335 which supports the transfer cylinder 41, because this cylinder will still receive pressure from the pressure supply main 433 through line 435, passage 451 of "impression" valve disc 49a and line 453. However, the piston 321 in pressure chamber 319 and supporting impression cylinder 42 will drop by reason of the fact that the line 459, valve passage 457 of "impression" valve disc 49a, and line 439 will now be in communication with the atmosphere through valve chamber 402 wherein the valve 410 is now open to the atmosphere through port 429 and valve 411 of chamber 403, being closed, will prevent pressure flow to chamber 402. The ink form rollers 40 will be moved away from the plate cylinder 38, since the operating handle 215 will be moved rearwardly (to the left with respect to Figures 13 and 14) by the following flow circuit arrangement.

The opening of valve 412 in chamber 404 will permit pressure to flow past that valve through passage 430 and into chamber 405. Valve 413 now being closed, this pressure will move through line 436 to port 438 of "ink" valve 50 and through passage 483 in the valve disc of that valve to line 481. From line 481, the pressure will flow through port 480 of "impression" valve 49, passage 479 and port 478 to line 471, whence the pressure will flow into chamber 476, moving the valve operating lever 215 rearwardly (to the left in Figure 7), thereby rotating the cam 220 to move the hangers 194 apart, thereby moving the ink form rolls 40 away from the plate cylinder 38. The movement of operating handle 215 described above will be permitted due to the fact that pressure is simultaneously relieved from chamber 470 through line 469, passage 467 in "ink" valve disc 50a, and thence through line 465, line 459, passage 457 of "impression" valve disc 49a, line 439, and valve chamber 402, now open to the atmosphere as described above.

Should a sheet be presented upon the trip finger 46 on the next cycle of operation of the trip mechanism 47, the sheet trip mechanism will rock rocker arm 362 back to the position shown in Figure 8, thereby moving the cams 421 back to the position shown in Figure 22, thereby changing the position of the valves in automatic valve mechanism 48 back to the position diagrammatically shown in Figure 13, so that the fluid flow will be as in that figure, thereby immediately re-lifting the impression cylinder 42 and moving the ink form rolls 40 back into engagement with the plate cylinder 38.

If no sheet is presented upon the trip finger 46 on the next cycle, the valves of automatic valve mechanism 48 will of course remain as shown in Figure 14, and the impression roll 42 will remain down and the ink form rolls will remain out of contact with the plate cylinder until a sheet is positioned upon the trip finger 46 at the proper moment in a subsequent cycle of operation of the trip mechanism 47.

Flow-circuits—transfer and impression cylinders held down—ink form rolls manually operable

Should the operator desire to drop the transfer cylinder 41 and the impression cylinder 42 and hold them downwardly during turning over of the press cylinders, and regardless of whether or not a sheet is positioned upon the trip finger 46 at the proper moment, the "impression" valve 49 may be moved to the position shown in Figure 15, wherein it is at "off" or at right hand position.

In this position of the valve, the pressure in chamber 319 which holds piston 321 and impression cylinder 42 upwardly will be exhausted through line 459, seat port 458 of "impression" valve 49, passage 457 of valve disc 49a and exhaust port 491 (to the atmosphere) in the valve seat. The pressure in chamber 336 which holds the piston 335 and transfer cylinder 41 upwardly will also be exhausted to atmosphere through line 453, seat port 452 of "impression" valve 49, valve disc passage 451 and exhaust port 490. Pressure line 435 will be closed by reason of the fact that a blank portion of the face of valve disc 49a will be moved opposite the valve seat end of that line. The valve seat end of pressure line 439 will also now be opposite a blank portion of valve disc 49a so that a change in the position of the valves of automatic valve mechanism 48 will not affect the position of the transfer cylinder 41 and the impression cylinder 42.

Pressure will be released from the pressure chamber 476 associated with the ink form roller operating lever 215, this exhaust flowing through line 471, valve seat port 478 of "impression" valve 49, passage 479 of valve disc 49a and exhaust port 492 of the valve seat. The end of line 481 which enters the valve seat of "impression" valve 49 will be opposite a blank portion of the face of the valve disc 49a so that no change in the position of the valves of automatic valve mechanism 48 will affect the position of form roll operating handle 215. Since the pressure chamber 470 also associated with the form roller operating lever 215 is now in communication with the atmosphere through line 469, passage 467 of "ink" valve 50, lines 465 and 459, passage 457 and exhaust port 491 of "impression" valve 49, the ink form roll operating lever 215 is under no pressure whatever and may be operated by hand to whatever position is desirable in the turning over of the press cylinders.

Flow circuits—cylinders up—ink form rolls off

In some instances, it is desirable to have the hand lever 125 associated with the ink form rolls 40 free for manual operation, and while the cylinders 41 and 42 are in upward position. To operate the press in this manner, "ink" valve disc 50a would be moved to the "on" or right hand position as shown in Figure 16. With the valve in this position, if "impression" valve 49 is in "on" or normal running position, the chamber 476 associated with form roller operating lever 215 will be in communication with the atmosphere through line 471, "impression" valve disc passage 479, line 481, and "ink" valve disc passage 483, now open to atmosphere through exhaust port 484. Chamber 470 will communicate with the atmosphere through line 469, "ink" valve disc passage 467, and exhaust port 495 in the "ink" valve seat. This position of the ink form rolls, with the transfer and impression cylinders up, is desirable during the performance of numerous preliminary operations upon the press.

In order to move both the transfer cylinder 41 and the impression cylinder 42 downwardly and to have the operating lever 215 free for manual operation, the handle of the "impression" valve 49 and the handle of the "ink" valve 50 are moved to the right. In this position, all of the lines communicating with chambers 319, 336, 470 and 476 will be open to the atmosphere so that no pressure will be present in any of these chambers.

It will be understood that the invention is not limited to the details of construction shown in the drawings and that the examples of the use of the machine and mechanisms which have been given do not include all of the uses of which they are capable, and that the phraseology employed in the specification is for the purpose of description and not of limitation.

Matter disclosed but not claimed herein may be claimed either in said Patent No. 2,205,720, issued on said original Goebel and Wilckens application, Serial No. 103,592 or in Patent No. 2,310,363, issued Feb. 9, 1943 on our application for Printing press dampening roll control, Serial No. 333,253, filed of even date herewith, which is also a division of said original application.

We claim:

1. The combination in a printing press includ-

ing a printing couple, of a roll to deliver ink to an element of said couple, and fluid pressure operated means to control the position of said roll with respect to said couple.

2. The combination in a printing press including a printing couple, of a roll to deliver ink to an element of said couple, fluid pressure operated means to control the position of said roll with respect to said couple, means to deliver sheets to said couple, and valve mechanism operable in accordance with the delivery of sheets to said couple to control pressure flow to said means.

3. The combination in a printing press including a printing couple, of a roll to deliver ink to an element of said couple, fluid pressure operated means to control the position of said roll with respect to said couple, means to deliver sheets to said couple, automatic valve mechanism operable in accordance with the delivery of sheets to said couple to control pressure flow to said means, and a manual valve to selectively control the operation of said automatic valve mechanism.

4. The combination in a printing press including a printing couple, of an ink roll, means to support said roll in contact with an element of said printing couple, fluid pressure operated means to control the position of said last-named means, said fluid pressure operated means being disconnectable to permit manual operation of said first-named means.

5. The combination in a printing press, of a printing couple, an inking cylinder to deliver ink to said printing couple, a cylinder shaft, a housing adjacent each end of said shaft to support said cylinder, an anti-friction bearing positioned within each of said housings to support the cylinder for axial movement on said shaft, cooperating means including rotatable elements on each of said housings and said shaft to guide said cylinder during axial movement of the latter with respect to said shaft, and means to rotate said shaft and move said cylinder axially thereof during such rotation.

6. The combination in a printing press, of a printing couple, a roll to deliver ink to an element of said couple, a hanger for said roll, cam means to move said hanger and roll from said element, means to lock said hanger and roll against said element, and means to operate said cam means by fluid pressure.

7. The combination in a printing press, of side frames, a printing couple, a plurality of ink rolls, a pair of oppositely disposed hangers pivoted to said frame to support said rolls, cam means to control the position of said hangers and rolls with respect to said printing couple, and a pressure cylinder and piston, one of which is fixed to said frame and the other of which is operatively connected to said last-named means to operate the same.

8. The combination in a printing press including frame elements, a printing couple, and a roll

to deliver ink to a cylinder of said couple, of means to adjust the position of said roll comprising a socket member, means to support said socket member on the frame element and move the same circumferentially of the cylinder of the printing couple, and means to move said roll longitudinally of said socket member and radially of the printing couple cylinder.

9. The combination in a printing press including a printing couple and a roll to deliver ink to a cylinder of the couple, of means to adjust the position of the roll with respect to the cylinder comprising a frame member having an arcuate groove therein extending circumferentially with respect to the cylinder, a socket member engaged in the groove, means to support said socket member on said frame member and to move the same along the groove, said socket member having a bore therein extending substantially at right angles to the groove, a roll carrying bracket in the bore, and means to move said bracket in the bore to move the roll radially of the cylinder.

10. The combination in a printing press, of a frame, a printing couple, an inking cylinder to deliver ink to said printing couple, a shaft on which said cylinder is mounted, means to rotate said shaft, a worm gear fixed to said shaft, a worm wheel meshing with said worm gear, an eccentric on said worm wheel, a rocker arm pivoted on said frame and operated from said eccentric, said rocker arm engaging said inking cylinder to cause the latter to be reciprocated on said shaft as the shaft is rotated.

11. The combination in a printing press including a printing couple and a roll to deliver ink to a cylinder of the couple, of means to adjust the position of the roll with respect to the cylinder comprising a frame member having an arcuate groove therein extending circumferentially with respect to the cylinder, a socket member engaged in the groove, means to support said socket member on said frame member and including an eccentric to move the same along the groove, said socket member having a bore therein extending substantially at right angles to the groove, a roll carrying bracket in the bore, and means to move said bracket in the bore to move the roll radially of the cylinder.

12. The combination in a printing press including side frames, of a roll supporting structure comprising a socket member fixed with respect to one side frame to receive one end of the roll, a socket member having a limited sliding movement in the other side frame along a line axially of the roll and adapted to support the adjacent end of the roll when in inward limit position and to be free of the adjacent end of the roll in its outer limit position, and means to hold said second socket member in such inward position.
